UNITED STATES PATENT OFFICE

HIRAM WALKER, OF CLEVELAND, OHIO, ASSIGNOR, BY MESNE ASSIGNMENTS, TO HUPP MOTOR CAR CORPORATION, OF CLEVELAND, OHIO, A CORPORATION OF VIRGINIA

AIR INTAKE FOR CARBURETORS THROUGH HOOD LOUVERS

Application filed September 6, 1928. Serial No. 304,182.

The invention relates in general to automobiles and, more particularly, to a new system of carburetion for the internal combustion engines thereof.

With the internal combustion engines in modern automobiles, it is desirable to take the air for the carburetor from a point which is reasonably cool and of substantially even temperature. Since the temperature inside of the hood varies to a greater extent than the temperature outside the hood, it is desirable to take the air for the carburetor from a point outside the hood.

According to the invention the louvers which are present in the sides of the hood in most modern automobiles are utilized in a simple and efficient manner for conveying air from outside the hood to the carburetor. The construction is such that neither the appearance of the automobile nor the ease of opening or closing the hood is affected in any way.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which—

Fig. 1 is an elevation of the front part of a type of modern automobile with parts broken away for clearness; and

Fig. 2 is a section on the line 2—2 of Fig. 1. In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily

for purposes of disclosure, it will be understood that the structure may be modified in various respects without departure from the broad spirit and scope of the invention as hereinafter defined and claimed.

Referring now to the drawings, the automobile shown for purposes of illustration is a modern type having a radiator 10 in front followed by a hood denoted generally by 11. The hood 11 is followed by the usual cowl 55 and body (not shown). The hood comprises a top section 12 and side sections 13 hinged thereto by hinges 14. The hood is provided with sets of horizontally extending, downwardly opening louvers 15 for cooling, as is well understood.

The automobile is provided with a sill 115 extending from the radiator 10 to the cowl, to which the sides 13 of the hood are fastened, as is well understood. Each side section 70 of the hood 11 is provided with a handle 16 to aid in raising and lowering the hood. Disposed in the hood, as is well understood, is an internal combustion engine 17 of any desired construction, having a suitable carburetor 18 secured thereto. The carburetor is provided with an air inlet pipe 19 ending in a cylindrical portion 20 and provided with an annular flange 21 spaced from the end, the end of this pipe opening toward the side of 30 the hood. The inner face of one side 13 of the hood is provided with a generally rectangular air box 22 having an opening 23 adapted to register with the pipe 19. This box is large enough to cover a sufficient number of louvers 15 to allow the required amount of air to pass into the carburetor. A washer 123 of non-squeaking material is secured to the air box around the opening 23.

In order to maintain a substantially air-tight connection between the air box 22 and the inlet pipe 19 irrespective of the weaving or other motion of the vehicle a sleeve 24, having an outer flange 25, is slid over the cylindrical portion 20 and a helical spring 26 is placed between the flanges 21 and 25 to yieldably hold the outer flange 25 against the washer 123 when the hood is closed. The sleeve 24 is provided with a slot 27 and the cylindrical portion with a pin 28 disposed in 95 100

said slot to limit the outward movement of said sleeve when the hood is raised.

Thus it will be seen that the hood section 13 may be raised and lowered without any extra attention to the connection between the air box and air intake pipe. The air box is separated from the air intake pipe by merely raising the hood and these parts are properly connected together by merely lowering the hood in the ordinary way. The yielding construction insures an air tight connection whenever the hood is closed irrespective of vibration and weaving of the car. Furthermore, the downwardly opening louvers protect the carburetor air intake from rain and dirt.

It will be seen that the arrangement does not in any way detract from the appearance of the automobile since it is entirely hidden from view. The arrangement furthermore increases the volumetric efficiency of the motor and keeps it cooler. In addition, it causes better and more uniform carburetion, since the temperature variation of the air outside is less than under the hood. Furthermore, in hot weather the air outside is much cooler than under the hood and hence the performance of the engine is improved and high volumetric efficiency maintained.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A vehicle having in combination, a carburetor intake conduit, a hood enclosing said conduit and having a movable part formed with louvers therein for the passage of air, means carried by said hood for directing air flowing through said louvers into the intake conduit, and means forming a separable joint between the means aforesaid and conduit permitting unrestricted movement of said part.

2. A vehicle having in combination, a carburetor, a hood enclosing said carburetor and having a movable part formed with an opening in one wall thereof for the passage of air, means for receiving the air flowing through said opening and supplying the same to the carburetor, and means forming a separable joint between the means aforesaid and movable part of the hood permitting unrestricted movement of the latter.

3. A vehicle having in combination, a carburetor intake member, a hood enclosing the carburetor intake member, and having a movable part formed with an opening therein for the passage of air, a second member disposed beneath the hood in a position to collect

the air flowing through said opening, said second member having an outlet opening therein communicating with the conduit aforesaid, and means forming a separable joint between one of said members and movable part permitting unrestricted movement of the latter.

4. A vehicle having in combination, a carburetor, a hood enclosing said carburetor and having a movable part formed with an opening in one wall thereof for the passage of air, means for receiving the air flowing through said opening and supplying the same to the carburetor, means forming a separable joint between the means aforesaid and movable part permitting unrestricted movement of the latter, and means forming a tight seal for said joint.

5. A vehicle having in combination, a hood comprising a movable part having an opening therein for the passage of air, a member disposed beneath the hood and secured to the movable part for receiving the air flowing through said opening and having an opening in one wall thereof, a carburetor intake conduit having the inlet end thereof extending in juxtaposition to the member in the normal position of the part aforesaid and adapted to register with the opening in said member for receiving the air flowing into the latter, said member and conduit free from connection with each other permitting unrestricted movement of the movable part aforesaid, and means carried by one of said members and surrounding the inlet end of said conduit for forming a tight seal.

6. A vehicle having in combination, an air intake conduit, a hood enclosing said conduit and having a movable part formed with an opening therein for the passage of air, means for conducting the air flowing through said opening into the intake conduit including a member forming a chamber having an opening therein normally arranged in registration with the inlet end of said intake conduit, said member free from connection with the end of said conduit permitting free movement of the part aforesaid, means surrounding the opening in said member and the inlet end of said conduit forming a detachable seal, said means including a spring influenced element carried by one of said members and engageable with the other of said members.

7. A vehicle having in combination, an air intake conduit, a hood enclosing said conduit and having a movable part formed with a louver therein for the passage of air, means for collecting the air flowing through said louver and conducting the same into the intake conduit including a chamber fixed to the movable part of the hood in communication with said louver opening and having an outlet opening therein registering with the inlet end of said intake conduit, said chamber and intake conduit being free from connec-

tion permitting free movement of said movable part, a seal for the joint between the inlet end of the intake conduit and said chamber, said seal including a tubular member sleeved upon the end of said conduit and engageable with a portion of said chamber around the outlet opening therein, and yieldable means normally urging said tubular member into firm engagement with the portion aforesaid of said chamber.

8. A vehicle having in combination, a hood having a movable part formed with an opening therein, a carburetor intake conduit arranged beneath the hood with the inlet end thereof in juxtaposition to the opening in the hood for receiving air passing through the latter, and sealing means between the inlet end of the conduit and opening separable upon movement of the movable part of the hood.

20 In testimony whereof I have hereunto set my hand.

HIRAM WALKER.
